UNITED STATES PATENT OFFICE

2,200,017

LAWN SPRINKLER

Anton Anderson, Chicago, Ill.

Application November 13, 1939, Serial No. 304,222

2 Claims. (Cl. 299—68)

This invention relates to improvements in lawn sprinklers and more especially a device having a rotatable baffle adapted to give wide dispersion and diffusion to water issuing therefrom.

5 Among the features of my invention is the provision of an improved baffle support offering very little, if any, obstruction to the water. With this construction the sprinkler will not only cover an area of large circumference but will evenly 10 sprinkle said area.

Another feature of my invention is improved adjusting means for the baffle permitting free but steady rotation thereof.

15 Another feature of my invention is extreme simplicity in construction and design of the apparatus permitting cheap manufacture and assembly thereof.

Another feature of my invention is the provision 20 of an improved antifriction support for the sprinkler enabling it to be easily drawn over the lawn or other surface for change of position.

Other features and advantages of my invention will appear more fully as I proceed with my specification.

25 In that form of device embodying the features of my invention shown in the accompanying drawing, Fig. 1 is a view in perspective of the device; Fig. 2 is a view in side elevation of the upper end of the device; and Fig. 3 is a view taken 30 as indicated by the line 3 of Fig. 2.

In that form of device embodying the features of my invention shown in the accompanying drawing, 10 indicates a vertical pipe with a jet 11 on the upper end thereof. 12 indicates in 35 general a rotatable baffle supported on the upper end of the jet and adapted to be engaged and rotated by a stream of water issuing from the jet. 13 indicates a thin bowed sheet metal supporting arm having its lower end connected to the jet and its upper end carrying a depending adjustable screw or trunnion 14 with its lower end pointed and engaging a depression or socket 12a in the upper surface of the baffle 12.

The lower end of the pipe 10 is supported on 45 a horizontal base member 15 with its ends bent downwardly as indicated by 15a carrying a roller 16 mounted therebetween. The lower end of the pipe 10 is supplied from a horizontal supply pipe 17 connected to the hose 18.

50 The wide roller 16 permits the device to be drawn easily over a lawn or soft surface by pulling the hose 18 without damage to the supporting surface.

The member 13 is made of sheet metal which is 55 of very thin gauge. Sufficient strength and

rigidity is obtained by making the member of substantial width. The long dimension of the member is radial with respect to the axis of the jet so water issuing therefrom encounters very little, if any, obstruction from the member 13. 5 In other words, the member 13 presents its thin edge to the direction of travel of the water and therefore shades or obstructs the sprinkling action to a very fine degree, if at all.

The upper end of the member 13 is bent at 10 right angles as indicated by 13a and perforated to receive the screw 14 which is held in position by the lock nuts 19—19.

The lower end of the member 13 is also bent at right angles as indicated by 13b and also 15 perforated to go over the jet 11. It rests on the shoulder 11a of the jet and is held securely thereon by the nut 20.

The baffle 12 has a thickened part or block 12b on its rear side which contains the depression 12a 20 above described. The baffle 12 has the general shape of a propeller or fan blade designed to throw water issuing from the jet radially and the baffle is unsymmetrical so that water issuing from the jet against the baffle will rotate the 25 latter. In order to permit such rotation the lower end of the baffle carries a collar 12c surrounding the upper end of the jet 11 and resting on the nut 20. The screw 14 is adjusted to support the baffle and permit free rotation thereof.

30 While I have shown and described certain embodiments of my invention, it is to be understood that it is capable of many modifications. Changes, therefore, in the construction and arrangement may be made without departing from the spirit and scope of the invention as disclosed in the appended claims, in which it is intended to claim all novelty inherent in the invention as broadly as permissible, in view of the prior art.

35 What I claim as new and desire to secure by 40 Letters Patent is:

1. A lawn sprinkler, including: a vertical pipe; a jet nozzle carried on the upper end of the pipe having external threads thereon; a thin bowed sheet metal supporting arm having its major portion lying in a vertical plane radial to the axis of the jet nozzle, the lower end of said arm being bent into a horizontal plane and perforated to receive the end of the jet nozzle through said 45 perforation, the upper end of said arm also being bent into a horizontal plane and perforated and lying over the jet nozzle; a lock nut on the jet nozzle holding the lower end of said arm thereon; a baffle rotatably mounted on the jet nozzle; a bearing block on the baffle; and a depending 50

55

trunnion adjustably mounted in the perforation in the upper end of said arm, the lower end of said trunnion engaging the bearing block on the baffle.

5. 2. A lawn sprinkler, including: a vertical pipe; a jet nozzle carried on the upper end of the pipe; a thin bowed sheet metal supporting arm having its major portion lying in a vertical plane radial to the axis of the jet nozzle, the lower end 10 of said arm being bent into a horizontal plane and perforated to receive the end of the jet nozzle

through said perforation, the upper end of said arm also being bent into a horizontal plane and perforated and lying over the jet nozzle; means for holding the lower end of said arm on said jet nozzle; a baffle rotatably mounted on the jet nozzle; a bearing block on the baffle; and a depending trunnion adjustably mounted in the perforation in the upper end of said arm, the lower end of said trunnion engaging the bearing block on the baffle.
